UNITED STATES PATENT OFFICE.

FRANK J. BOFSKY, OF DETROIT, MICHIGAN.

POWDER-PUFF.

1,398,712.

Specification of Letters Patent. Patented Nov. 29, 1921.

Application filed February 5, 1921. Serial No. 442,672.

To all whom it may concern:

Be it known that I, FRANK J. BOFSKY, a citizen of the United States of America, residing at Detroit, in the county of Wayne 5 and State of Michigan, have invented certain new and useful Improvements in Powder-Puffs, of which the following is a specification, reference being had therein to the accompanying drawings.

10 This invention relates to powder puffs, such as are commonly employed to apply face powder to the skin.

It is the object of the invention to provide a powder puff having upon one side a facing of lamb's wool or the like material, and having its other face lined with a suitable fabric to which a pocket is secured to receive a small mirror, the latter occupying a concentric relation to the powder puff when 20 engaged in said pocket.

In the drawings:

Figure 1 is a perspective view showing the rear or lined face of the powder puff;

Fig. 2 is a rear view of the mirror engage- 25 able with the powder puff;

Fig. 3 is a cross section view of the powder puff showing the mirror inserted in said pocket.

In these views the reference character A 30 designates a circular piece of lamb's wool, felt, or the like, which provides the facing of the powder puff, and B is a circular lining for the rear surface of the article, said lining being formed of satin or of some other 35 suitable fabric. A disk B' of flannel or some other fairly heavy fabric is stitched against the inner face of the lining B to serve as a filler and give more body to the powder puff. A piece of fabric C, prefer- 40 ably of the same material as the lining, is peripherally sewed to the latter and forms a segmental pocket, somewhat greater than a semi-circle, in which may be inserted a small disk shaped mirror D, said mirror 45 having a fabric loop E projecting from the back thereof, and providing a finger grip to facilitate insertion or removal of said mirror in or from said pocket. Said pocket C has a hem internally formed at its upper edge 50 within which a strip of elastic webbing C' is extended across the pocket, said webbing being stretched by insertion of the mirror D into the pocket and preventing said mirror coming out except in response to a muscular effort. That the height of the pocket 55 exceeds its radius is an important feature of

the invention since the length of the inlet to the pocket is thus somewhat less than the diameter of the mirror which is proportioned to snugly fit the pocket, and the strip 60 C' must therefore be stretched in either inserting or removing the mirror.

It is preferred to roll the marginal portion of the member A to peripherally overlap the lining B and pocket C as indicated 65 at E', the rolled portion being stitched to said lining as indicated at F. Thus a circular depression is formed in the rear face of the powder puff by the rolled edge E', within which depression the mirror D fits 70 snugly when engaged with the pocket C.

The described article facilitates the use of a powder puff by mounting upon the latter a mirror, which may be used to advantage in conjunction with the powder puff. Also 75 when the powder puff is being used, and the mirror D is removed from the pocket C, the said pocket may be engaged by the fingers of the user, and the article thus conveniently handled. 80

What I claim as my invention is:

1. A powder puff having a facing of soft material, peripherally rolled to overlap the rear face of the article, a lining for said rear face arranged within a depression formed 85 by said rolled portion of the facing, and a pocket for a mirror secured to said lining within said depression.

2. A powder puff having a facing of soft material, and having a fabric lining for its 90 rear face, and a segmental pocket secured to said lining, the peripheral portion of said facing being rolled to marginally cover said rear face, and being stitched to said lining forming a circular depression within which 95 said pocket is located, and a disk shaped mirror insertible in said pocket and fitting snugly in said depression when so inserted.

3. A powder puff, having a segmental pocket for a disk mirror, the height of said 100 pocket being greater than its radius and an elastic member extending across the mouth of said pocket to retain the mirror.

4. A powder puff having a segmental pocket for a disk mirror, the height of said 105 pocket exceeding its radius, and a hem being formed interiorly of the pocket extending across the mouth thereof, and an elastic strip within said hem secured at each side of the pocket and serving to retain said mirror. 110

5. A powder puff having upon one side a circular facing of soft material and cen-

trally provided upon its opposite side with a segmental pocket for receiving a disk mirror, said pocket being shaped and proportioned to restrain the mirror from accidental disengagement in any position of the powder puff.

6. A powder puff having a segmental

pocket for a disk mirror, the height of said pocket exceeding the radius thereof, and the mouth of said pocket forming a chord of 10 length less than the diameter of the pocket.

In testimony whereof I affix my signature.

FRANK J. BOFSKY.
